UNITED STATES PATENT OFFICE

WILLIAM E. SHORE, OF WEST NEW BRIGHTON, NEW YORK

ROTARY MACHINE

Application filed March 20, 1930, Serial No. 437,583, and in Canada April 5, 1929.

The principal objects of this invention are to devise an extremely compact self-contained rotary machine which will operate continuously at a high degree of efficiency at very high speed and which will not be detrimentally subject to wear and which will be particularly effective in the preparing of liquid hydrocarbons for combustion and also useful for other purposes.

10 A further and very important object of the present invention is to enhance the efficiency of the type of rotary compressor or vacuum machines wherein a single vane operates within a profiled cylinder.

15 A further object of the invention is to incorporate in a machine of this type an oil pumping element which will utilize the peculiar motions set up therein in operation to pump a positive supply of oil which may be absorbed by the machine or be directed to an independent point as desired depending on the character of the work the machine is called upon to perform.

20 A still further and important object of the present invention is to obviate the serious difficulties met with in the close-coupling of a rotary pumping machine and an electric power element incident to the leakage of the mediums being handled and over-heating of the motor whereby the motor will not only be adequately cooled and ventilated but will be very definitely protected from contamination by the handled medium.

25 The principal feature of the invention consists in the novel construction and arrangement of parts wherein a single vane rotatably operated in a profiled cylinder by a transversely-slotted eccentrically-disposed rotor is provided with a disc at one end which is confined between two bearing surfaces against lateral thrusts maintaining the working outer ends of the single vane in true parallel relation with the profiled cylinder wall.

30 A further feature of importance consists in providing a roller member mounted on a fixed bearing and operating in a slot in the disc member in rolling contact with the walls thereof to definitely maintain the true

working position of the vane within the cylinder.

A further and important feature of the invention consists in providing a rotary pumping element or machine which is directly incorporated in a driving motor or element. 55

A still further and important feature of the invention resides in the novel arrangement of ports and passages whereby the roller member effects the displacement of oil or other fluid medium. 60

A still further feature consists in the novel construction whereby the escape of oil from the pump into the driving motor is avoided. 65

Another and important feature consists in the novel construction and arrangement of parts whereby an effective circulation of air through the motor is maintained to effect the cooling thereof. 70

In the drawings, Figure 1 is an elevational part sectional view of a complete unit constructed in accordance with this invention.

Figure 2 is a cross section taken on the line 2-2 of Figure 1 showing the arrangement of the vane and roller support. 75

Figure 3 is a cross section similar to Figure 2 on the line 3-3 of Figure 1 showing the arrangement of the parts with the vane in a position at right angles to Figure 2. 80

Figure 4 is a cross section taken on the line 4-4 of Figure 1 showing the manner in which the oil escaping past the packing gland is returned to the pump.

Figure 5 is a mid-sectional detail of the closed end of the pump showing the supporting roller and an arrangement of ports for utilizing the action of the roller support in the slot for pumping fluids, and illustrating the various ports in register. 85

Figure 6 is a cross-sectional view taken on the line 6-6 of Figure 5.

Figure 7 is a cross sectional view similar to Figure 5 but showing the ports out of register. 95

Figure 8 is a mid-sectional view taken on the line 8-8 of Figure 7 showing the slot ports out of register with the stationary ports in the casing.

Figure 9 is a perspective detail of a vane 100

element constructed in accordance with this invention.

The present invention has been devised with a view to providing a "single" vane type of rotary machine of considerably enhanced efficiency over the previously known structures, these advantages being obtained by the arrangements set forth herein.

This application relates to improvements 10 in construction over the structure disclosed in my United States Patent 1,848,670 of March 8, 1932.

In carrying the present invention into effect 15 the casing 1 is turned with a cylindrical boss extension 2 which fits snugly and non-rotatably in a tubular end extension 3 of the electric motor 4, which is concentric with the motor shaft 5 extending axially through the boss 2.

20 The outward end of the casing 1 is bored to provide the profiled cylinder surface 6, the axis of which is spaced parallelly from the axis of the motor shaft 5.

The cylinder surface is formed in the manner set forth in my United States Patent No. 25 1,742,731 of January 7, 1930, and need not be described in detail herein except to say that the cylinder wall is profiled in order to co-operate with and provide for the accommodation of the single vane member in its rotation in the cylinder so that the wall will conform to the path defined by the extremities of the single vane and thus maintain a uniform seal therebetween.

30 35 The rotor 7 is partly recessed into the counterbore 8 in the inner wall of the casing 1 which is concentric with the motor shaft and the walls of this counterbore form a substantial seal with the engaging surfaces of the rotor.

40 45 The rotor is provided with a tubular or sleeve extension 9 which snugly encircles the shaft 5 of the motor and the end of the motor shaft may be threaded at 10 into a corresponding threaded inner portion of the rotor sleeve or may be secured thereto in any other well known manner as by keying and pressing thereon.

50 55 A roller bearing 11 snugly encircles the rotor sleeve 9 and fits snugly within an annular ring 12 which may be pressed, threaded or otherwise secured in the counterbore 13 in the boss extension 2 leading from the bottom of the counterbore 8. The annular ring is formed with an inturned flange 14, the outer face of which forms a substantial seal with the adjacent face of the rotor 7.

60 The rotor is thus supported on the motor shaft in a rigid unit therewith and the bearing 11 serves to support the working end of the motor shaft as well as the rotor in a very compact and efficient manner.

A single vane 15 is provided which is a snug sliding fit in the transverse slot 16 of the rotor 7.

The vane 16 is formed with a central hub portion 17 which is preferably faced to intimately engage the outer face of the rotor to form a substantial seal therewith and carried by the hub portion 17 is a concentric guide 70 disc or flange 18 which presents a smooth bearing surface on either side.

The outer side of the guide disc 18 is adapted to intimately engage the wall 19 of a counterbore formed in the end closure member 20 of the cylinder and an annular bearing ring 21 is secured at its outer periphery in the counterbore 22 of the cylinder casing by the inwardly projecting annular flange 22' of the closure member. The annular bearing flange thus secured extends inwardly and engages the inward side of the disc 18.

The disc is thus definitely held against lateral displacement but may be displaced radially in a direction at true right angles to the axis of the cylinder or shaft, and in this way the outer ends of the vane will be definitely maintained in true parallel relation to the surface of the cylinder wall 6 with which they co-operate.

50 55 A hub extension 23 is provided on the outer side of the guide disc 18 which extends into a recess 24 in the closure member 20 and a guide slot 25 is formed therein which extends in true right angular relation to the vane 15.

The walls of said slot are spaced parallelly apart and are connected at the ends by the curved walls 26, the radius of which is equal to one half the distance between the spaced 100 guide walls.

A short stub shaft 27 is secured firmly and non-rotatably in the closure member 20 in axial alignment with the cylinder axis, which as previously stated, is parallelly offset from the axis of the motor shaft.

105 The inner end of the stub shaft 27 extends into the guide slot 25 and is preferably faced to intimately engage the disc 18 centrally and has mounted thereon a roller bearing 28, the outer ring of which intimately engages the parallelly spaced walls of the guide slot 25 in a rolling contact and very definitely positions the vane in a true concentric position 110 in the cylinder. In this way when the rotor is being driven and the vane rotating in the cylinder, the vane will, by reason of the co-operation of the guide slot walls with the rigidly mounted roller, be constantly moved thereby to a "neutral" position and the vane proper will not actually engage the cylinder wall 6 in metal to metal contact, but will be definitely prevented from so doing by reason of the constant positioning influence of the 115 roller and guide slot.

120 It is important in this regard to note that the minimum of friction is set up between the roller and guide walls since a rolling contact will be obtained which will be unidirectional 125

and constant thus avoiding the wearing of flats on the contact surface of the roller.

Figures 2 and 3 show very clearly the manner in which the roller functions as a guiding element and illustrates the manner in which the guide-slot walls are being constantly displaced relative to the roller bearing.

The movement of the hub extension 23 creates a relative reciprocative movement between the guide slot 25 and the roller bearing and such movement results in a pumping action to displace oil filling said slot.

In the construction illustrated in Figures 5 to 8, the guide disc 29 is formed of a width considerably greater than the previously described guide disc 18 and the counterbore 30 of the head member is made correspondingly deeper in order to accommodate the larger disc. In this latter construction the same condition obtains as in the case of the guide disc 18 in that the side walls thereof rotatably and slidably engage the adjacent surfaces of the counterbore wall 19 and the annular bearing ring 21 in snug guiding contact.

The guide slot 25' in this case is formed in the disc which is the equivalent of the arrangement shown in Figures 2 and 3.

At each end of the guide slot 25' is formed a port 31 which opens outwardly toward the inner face of the counterbore wall 19 and these ports 31 are adapted to register successively with the arc-shaped fixed ports 32 and 33 in the closure member 20.

As indicated in Figures 6 and 8 it will be seen that the arc-shaped ports are semi-circular and terminate at their extremities a short distance from each other and are preferably confined to either side of a line passing through the axes of the cylinder and the motor shaft in order to obtain the maximum efficiency and proper timing of the inlet and outlet ports with the ports 31 as the disc 29 rotates.

The port 32 may be connected by suitable piping 34 to a supply tank of oil or other medium which it is desired to pump and a pipe 35 may extend from the port 33 and conduct the oil to any desired point either within the machine to be utilized therein for lubricating purposes or may be introduced in regulated quantities into the intake 1' of the pump, or the pipe 35 may lead to points independent of the pump.

It will readily be understood on reference to the drawings that a very positive pumping action will be set up by the relative movement of the guide slot walls and guide roller, the latter acting in the capacity of a piston which alternately displaces the oil from first one end of the guide slot and then the other as the respective ends and ports 31 thereof are carried past the discharge port 33. It will be noted that as each of the ports 31 are moving past the inlet arc-shaped port 32, the guide roller will be receding in the slot rela-

tive to the said port 31, while at the same time it will be relatively advancing toward the opposite port 31 which is in register with the discharge port 33 so that a definite supply of oil will be handled each rotation of the machine.

In view of the close-coupled relation of the motor and pumping elements it is imperative that the windings of the motor be protected in an adequate manner from contact with the oil or medium handled by the pump and it is furthermore desirable to make special provision for the adequate cooling of the motor in order to obtain the maximum degree of efficiency.

For this purpose an annular packing ring 37 is provided which snugly encircles a short sleeve portion 39 arranged between the bearing 11 and a centrifugal impeller member 40 arranged on the motor shaft 5. The packing ring 37 is formed with a tubular extension 41 which extends into an axial bore 42 in the casting hub 2 either pressed therein or threaded as desired. A pair of spaced annular grooves 43 and 44 are formed in the inner encircling wall of the packing ring and the inner groove 44 carries a suitable packing material 44' which snugly engages the sleeve 39 in sealing contact.

The groove 43 forms a circumferential recess encircling the sleeve 39 on the outward side of the packing ring and any oil or vapour which might possibly find egress past the packing ring will enter the groove recess 43.

A duct 43' leads from the lower portion of the groove 43 to a passage 45 extending circumferentially of the packing ring 37, (see Figure 4) and connects with a passage 46 in the pump casing 1 which leads to a passage 47 which conducts the oil directly into the intake 1' of the cylinder. In this way the groove recess 43 is constantly under the vacuum influence of the intake and oil or vapour finding its way thereto will be immediately drawn therefrom back into the machine.

It will be further noted that there will be a constant tendency for atmospheric air to enter the groove 43 from the motor side between the sleeve 39 and the outer wall 48 of the groove 43 due to the vacuum condition existing in the latter and this will have the further desirable effect of constantly cleansing this portion of the sleeve 39 preventing any possibility of oil working its way along the same toward the motor, and there is no possibility of the motor becoming contaminated with oil.

A plurality of openings 50 are arranged in the outer wall of the motor casing in direct radial alignment with the impeller member 40. A second series of openings 51 are formed in the end wall of the motor casing encircling the tubular extension thereof and an annular baffle or divergence disc 52 is fitted snugly within the motor casing against the annular

shoulder 53 and forms a partition between the sets of openings 50 and 51. The inner periphery of the annular baffle disc 52 is spaced from the sleeve 39 of the shaft 5 and forms an annular passage 54 through which air from the openings 51 passes to the impeller.

With this arrangement when the motor is operating the impeller thrusts air out through the openings 50 and draws a cool 10 supply in through the openings 51, the disc 52 serving to direct the incoming supply to the central portion of the impeller so that a very effective circulation is obtained and the efficient operating temperature of the motor 15 will be maintained.

A machine such as described will be found to present many advantages particularly due to its ability to operate continuously at extremely high speed.

20 The vane is at all times definitely supported in a neutral position against metallic contact with the cylinder wall by the rolling support described which absorbs the very heavy thrust with the minimum of friction and consequently wear is reduced to a minimum and this reduction of friction in the working parts is transformed into work so that a speed of operation is economically obtained which was hitherto impossible.

25 It is therefore possible to subject a fluid medium to instantaneous changes of pressure and to raise its temperature so rapidly by compression that substantially all the generated heat is maintained in the treated medium and little or no heat is transferred to the surrounding body of the pump in a manner which closely approaches the ideal adiabatic condition. This condition is further enhanced due to the enormous volume of 35 which the pump is capable of handling relative to its size and due to speed alone so that the contact area presented by the pump to the medium will be extremely small.

In this way the energy consumed in the 40 driving machine may be converted or transformed with very small loss into the preparing of the liquid hydrocarbon or fuel to a condition of heat and vapour tension on the discharge, and a decided advance is thus represented when applied to the furnace or combustion engine arts or that pertaining to the distillation of liquids.

What I claim as my invention is:—

1. A rotary machine, comprising in combination a casing formed with a cylinder, a transversely slotted rotor eccentrically arranged in said cylinder, a single vane member reciprocably mounted in the slot in said rotor, said vane member having a transverse slotted portion extending beyond the cylinder, said vane member having axially spaced plane guide surfaces extending therefrom in right angular relation to the impeller axis, means engaging the opposite walls of said slot beyond said cylinder to determine the re-

ciprocal movement of the vane member in the rotor and guide means co-operating with each of said axially spaced plane guide surfaces to definitely maintain said impeller with its outer ends in true parallel relation to the cylinder wall. 70

2. A rotary machine, comprising a casing formed with a cylinder, a transversely slotted rotor eccentrically arranged in said cylinder, a single vane member reciprocably mounted in the slot in said rotor, bearing means for maintaining said vane member with its axis in true parallel relation to the rotor axis, and roller means operatively engaging said vane member at one end only of said cylinder for maintaining said vane in a neutral position in said cylinder, said bearing and roller means forming an active co-operation in controlling the position of said vane member. 75

3. A rotary machine, comprising a casing formed with a cylinder, a transversely slotted rotor eccentrically arranged in said cylinder, a single vane member reciprocably mounted in the slot in said rotor, roller means fixed to the cylinder casing at one end only of the cylinder in axial alignment with the cylinder axis operatively engaging said vane member at one side and supporting said member in a centralized position within said cylinder, and bearing means for maintaining said vane member with its axis in true parallel relation to the rotor axis in opposition to thrusts exerted by said single roller means. 90

4. A rotary machine, comprising a cylinder casing, a rotor eccentrically mounted in said casing and having a slot extending transversely through its axis, an impeller having a vane slidable in said slot in said rotor and extending beyond the periphery of said rotor on either side thereof, said impeller having parallelly spaced surfaces right angularly arranged with respect to said vane, walls enclosing said surfaces forming a displacement chamber, and means fixed in said casing and disposed in said displacement chamber, engaging said surfaces in rolling contact to relieve the vane from centrifugal thrust against the cylinder wall, said means forming a displacement pumping member in said chamber. 100

5. A rotary machine, comprising a casing formed with a cylinder, a transversely slotted rotor eccentrically arranged in said cylinder, a single vane member reciprocably mounted in the slot in said rotor, said vane member having a transversely extending bottomed slot formed therein, means closing the outer side of said slot and means mounted in a fixed position relative to said cylinder extending into said slot and engaging the walls thereof in rolling contact to maintain said vane member centralized in the cylinder, said means forming a displacement pumping member in said slot. 110

6. A rotary machine, comprising a casing 120

formed with a cylinder, a transversely slotted rotor eccentrically arranged in said cylinder, a single vane member reciprocably mounted in the slot in said rotor, a hub at one side of said vane having a bottomed parallel-walled slot formed therein extending in right-angular relation to the vane, a cap closing the outer end of said cylinder and slot, and a roller member mounted on said cap in axial alignment with the cylinder axis and engaging the walls of said hub slot in rolling guiding contact, said roller fitting snugly between the bottom of said slot and said cap and forming a displacement piston in the slot.

7. A rotary machine, comprising a casing formed with a cylinder, a transversely slotted rotor eccentrically arranged in said cylinder, a single vane member reciprocably mounted in the slot in said rotor, a hub at one side of said vane externally of the cylinder having a parallel-walled slot formed therein extending in right-angular relation to the vane, a cap closing the outer end of said cylinder, a stub shaft rigidly secured in said cap in axial alignment with the cylinder axis, a single roller bearing member mounted on and concentrically encircling said stub shaft and having its periphery engaging the walls of said slot in progressive rolling thrust contact, and means co-operating with said vane member for maintaining its axis parallel to the rotor axis unaffected by the thrusts imposed on said vane member by said roller member.

8. A rotary machine comprising a casing formed with a cylinder, a transversely slotted rotor eccentrically arranged in said cylinder, a single vane member reciprocably mounted in the slot in said rotor, and having a guide portion disposed externally of the cylinder, a roller means disposed externally of the cylinder operatively engaging said guide portion for maintaining said vane in a neutral position in said cylinder, and bearing means rigid with said vane member engaging fixed bearing surfaces and supporting the vane against axial thrust.

9. A rotary machine, comprising a casing formed with a cylinder, a transversely slotted rotor eccentrically arranged in said cylinder, a single vane member reciprocably mounted in the slot in said rotor, guide means operatively engaging said vane member for maintaining said vane in a neutral position in said cylinder, a guide disc rigid with said vane member and encircling said guide means and bearing means carried by said casing and engaging the side surfaces of said disc to support the vane against axial thrust, said guide disc and guide means being disposed in a substantially common plane at one side of the vane member whereby binding of said guide disc between said bearing means due to the thrusts exerted by said guide

means in neutralizing the vane is minimized.

10. A rotary machine, comprising a casing formed with a cylinder, a transversely slotted rotor eccentrically arranged in said cylinder, a vane reciprocable in said rotor slot, a guide disc rigidly carried by said vane at the end of said rotor, a transverse slot in said disc, roller means engaging the walls of said slot to neutralize the transverse position of said blade in the cylinder, and means carried by said cylinder casing engaging the faces of said guide disc to confine said vane against thrust and displacement longitudinally in said cylinder.

11. A rotary machine comprising a casing formed with a cylinder, a transversely slotted rotor eccentrically arranged in said cylinder, a vane reciprocable in said rotor slot, a guide disc rigidly carried by said vane at the end of said rotor, a transverse slot in said disc, and means fixed to said casing in axial alignment with the cylinder axis engaging the walls of said disc slot in guiding contact to neutralize the transverse position of said vane in the cylinder, and means carried by said cylinder casing for engaging said disc on either side to definitely support the vane with its end extremities in true parallel relation to the cylinder wall.

12. A rotary machine, comprising a casing formed with a cylinder, a transversely slotted rotor eccentrically arranged in said cylinder, a single vane member reciprocably mounted in the slot in said rotor, said vane member having a transverse slot formed therein, means mounted in a fixed position relative to said cylinder and engaging the walls of said slot in rolling contact to maintain said vane member centralized in the cylinder, and stationary ports in the cylinder casing adapted to register periodically with the ends of said vane slot as the rotor rotates.

13. A rotary machine, comprising a casing formed with a cylinder, a transversely slotted rotor eccentrically arranged in said cylinder, a single vane member reciprocably mounted in the slot in said rotor, said vane member having a transverse slot formed therein, means mounted in a fixed position relative to said cylinder and engaging the walls of said slot in rolling contact to maintain said vane member centralized in the cylinder, arc-shaped ports in the cylinder casing arranged one each side of the cylinder axis, and passages in the end walls of said guide slot adapted to concurrently communicate with the arc-shaped ports.

14. A rotary machine, comprising a casing formed with a cylinder, a transversely slotted rotor eccentrically arranged in said cylinder, a single vane member reciprocably mounted in the slot in said rotor, a hub at one side of said vane having a parallel-walled slot formed therein extending in right-angular

relation to the vane, a cap closing the outer end of said cylinder, a roller member mounted on said cap in axial alignment with the cylinder axis and engaging the walls of said hub slot in rolling guiding contact, and a plurality of stationary ports in the wall of said cap arranged in oppositely disposed relation and extending in a path concentric with the cylinder axis, said oppositely arranged ports being adapted to communicate concurrently with the opposite ends of said guide slot.

15. A rotary machine, comprising a casing formed with a cylinder, a transversely slotted rotor eccentrically arranged in said cylinder, a single vane member reciprocably mounted in the slot in said rotor, a hub at one side of said vane having a parallel-walled slot formed therein extending in right-angular relation to the vane, a cap closing the outer end of said cylinder, a roller member mounted on said cap in axial alignment with the cylinder axis and engaging the walls of said hub slot in rolling guiding contact, a peripheral guide flange carried by said hub and engaged 20 on one side by said cap member, and means carried by the casing engaging the other side of said guide flange, said flange supporting said vane with its end extremities in true parallel relation to the cylinder walls.

25 16. A rotary machine, comprising a casing formed with a cylinder, a transversely slotted rotor eccentrically arranged in said cylinder, a vane reciprocable in said rotor slot, a guide disc rigidly carried by said vane at the end 30 of said rotor, a transverse slot in said disc, means fixed to said casing in axial alignment with the cylinder axis engaging the walls of said disc slot in guiding contact to neutralize the transverse position of said vane 35 in the cylinder, means carried by said cylinder casing for engaging said disc on either side to definitely support the vane with its end extremities in true parallel relation to the cylinder wall, ports in the cylinder casing, and 40 passages leading from the end walls of said guide slot adapted to register with said ports.

45 17. A rotary machine, comprising a casing, a cylinder formed in said casing at the outer end, a slotted rotor journalled in the inner end of said casing out of alignment with the cylinder axis and arranged in said cylinder, a vane reciprocably mounted in the slot of said rotor and co-operating at each end with the cylinder wall, a cap closing the outer end of 50 said cylinder, said cap having a depressed inward portion, a guide disc rigidly carried by said vane and extending into the depressed portion of said cap and having its end face snugly engaging the end wall thereof, an 55 annular bearing ring secured between said casing and cap and snugly engaging said disc on its inner side, and means carried by said cap co-operating with said guide disc for maintaining said vane in longitudinal centralized relation to the cylinder walls.

18. A rotary machine, comprising a casing, a cylinder formed in said casing at the outer end, a slotted rotor journalled in the inner end of said casing out of alignment with the cylinder axis and arranged in said cylinder, a vane reciprocably mounted in the slot of said rotor and co-operating at each end with the cylinder wall, a cap closing the outer end of said cylinder, said cap having a depressed inward portion presenting a plane wall in 70 right angular relation to the cylinder axis, a guide disc rigidly carried by said vane and disposed in said cap depression said plane wall engaging the outer surface of said disc in guiding contact, bearing means engaging the inner side of said disc in guiding contact, a diametrical slot in the outer face of said guide disc in disposed right-angular relation to said vane, guiding means fixed to said cap and extending into said diametrical slot in said disc and engaging the opposite side walls thereof, and paired arc-shaped ports arranged in 75 the wall of said cap depression.

19. A rotary machine, comprising a casing, a cylinder formed in said casing at the outer end, a slotted rotor journalled in the inner end of said casing out of alignment with the cylinder axis and arranged in said cylinder, a vane reciprocably mounted in the slot of said rotor and co-operating at each 80 end with the cylinder wall, a cap closing the outer end of said cylinder, said cap having a centrally depressed inward portion presenting a plane wall in right angular relation to the cylinder axis, a guide disc rigid with said vane and disposed within said cap depression said plane wall engaging the outer surface of said disc in guiding contact, bearing means engaging the inner side of 85 said disc in guiding contact, a diametrical slot in the outer face of said guide disc in disposed right-angular relation to said vane, a stub shaft fixed rigidly in said cap and extending inwardly into said guide slot, a roller bearing mounted on said stub shaft 90 and snugly engaging the side walls of said guide slot in rolling guiding contact, a pair of arc-shaped ports in the disc-engaging wall of said cap and arranged one on each side of a line passing through the rotor and cylinder axes, and ports in said disc leading from the outer ends of said guide slot and adapted 95 to register with said arc-shaped ports.

20. A rotary machine, comprising a casing bored at one end to form a cylinder, a bearing arranged in the other end of said casing in eccentric relation to the cylinder axis and parallel therewith, an annular recess in the outer end of the cylinder wall, a slotted rotor concentrically journalled in said bearing and disposed in said cylinder, a vane in the slot of said rotor having a guide disc integral therewith and arranged at the outer side of 100 said rotor, an annular bearing ring arranged 105

in said cylinder wall recess and extending inwardly between said rotor and disc and engaging the latter in guiding contact, and a cap closing the outer end of said cylinder and having an annular flange entering the annular recess of said cylinder wall and securing said annular bearing ring therein, the inner wall of said cap engaging the outer surface of said guide disc in bearing contact.

21. A rotary machine, comprising a casing bored at one end to form a cylinder, a bearing arranged in the other end of said casing in eccentric relation to the cylinder axis and parallel therewith, an annular recess in the outer end of the cylinder wall, a slotted rotor concentrically journaled in said bearing and disposed in said cylinder, a vane in the rotor slot, a cap closing the outer end of said cylinder, means supported by said cap for supporting said vane in a centralized position in said cylinder with its ends in true parallel relation to the cylinder wall, a drive shaft extending into said casing concentric with said bearing and operatively connected with said rotor, an internally grooved ring member carried by said casing and encircling the drive shaft, and a passage leading from said ring groove to the intake of said cylinder.

22. A rotary machine, comprising a casing having a cylinder chamber at one end closed by a cap member at the outer end, a drive shaft extending into the casing from the other end in parallelly offset relation to the cylinder axis, the inner wall of said cylinder having stepped recesses a bearing fitting in one of said recesses, a rotor having a portion thereof extending into the other recess and having a sleeve extension concentrically encircling said drive shaft and supported in said bearing, said rotor being slotted, a vane reciprocably mounted in the rotor slot, and means supported by said cap member for guiding said vane against lateral and transverse thrust.

23. A rotary machine, comprising a casing formed with a cylinder, a transversely slotted rotor eccentrically arranged in said cylinder, a single vane member reciprocably mounted in the slot in said rotor, said vane having guide surfaces right-angularly arranged with relation thereto, and extending beyond the true cylinder cavity, rotatable guide means mounted in a fixed position and engaging certain of said right-angularly arranged surfaces in rolling contact to maintain said vane in a neutral position in said cylinder, and secondary guide means cooperating with the other of said right-angularly arranged surfaces to maintain said vane with its outer ends in true parallel relation to the cylinder wall.

WILLIAM E. SHORE.
